UNITED STATES PATENT OFFICE.

PERLEY D. CUMMINGS, OF PORTLAND, MAINE.

CAN-WIPI NG MACHINE.

SPECIFICATION forming part of Letters Patent No. 416,212, dated December 3, 1889.

Application filed March 11, 1889. Serial No. 302,803. (No model.)

To all whom it may concern:

Be it known that I, PERLEY D. CUMMINGS, a citizen of the United States, residing at Portland, in the county of Cumberland and State of Maine, have invented certain new and useful Improvements in Can-Wiping Machines; and I do hereby declare the following to be a full, clear, and exact description of the invention, such as will enable others skilled in the art to which it appertains to make and use the same.

My invention relates to machines for wiping the tops of cans in the operation of packing corn and other like substances.

The object of my invention is to construct a wiping-machine which shall remove all the moisture from the top of the can, and particularly from the groove or channel which surrounds the mouth of the can and in which the edge of the cap fits.

The several features of my machine are as follows, namely: a base on which the can is set and a lever for lifting it against the wiper; a rotating fly-frame having wiping-rolls journaled radially to it, said wiping-rolls being provided with rubber or other flexible ribs to fit the top of the can, pinions on the wiping-rolls, and a friction or other gear acting on said pinions and rotating in an opposite direction from the fly-frame, inner and outer concentric sleeves to which are attached the gear and the fly-frame, respectively, and band-pulleys attached to said sleeves. These parts rotate about a vertical fixed shaft, to the bottom of which is secured a plug for entering the mouth of the can. The wiping action of my machine is thus twofold—the fly-frame having a centrifugal motion which tends to throw outward the liquid taken up by the flanges on the wiping-rolls, and the rotary motion of the wiping-rolls themselves which tend to throw it upward and outward.

My invention consists of the various combinations of elements set forth in the claims.

I illustrate my invention by means of the accompanying drawings, in which—

Figure 1 is a perspective view of a machine embodying my invention. Fig. 2 is a vertical section. Fig. 3 is a view from underneath, and Fig. 4 is a detail of the wiping-roll.

The machine is mounted on a table or bench A by means of a standard G, having a horizontal arm at its upper end, to which is secured the fixed vertical shaft H, having on its lower end a plug I, whose lower end is tapered to move readily into the mouth of the can. Through this plug there are vents for relieving any excess of air in the can. Resting on the plug is the collar J, which acts as a bearing for the inner sleeve L', fitting the shaft H. Extending out from the lower end of the sleeve L' are the radial arms P, which support an annular gear, here shown as a friction-gear, though it is obvious that it may be a tooth-gear. Secured to the top of the sleeve L' is a band-pulley Q. Fitting outside of the sleeve L' is an outer sleeve P', to the lower end of which is connected what I here call the "fly-frame" L. It has radial arms and an annular rim of greater diameter than the can, which rim extends outside of and beneath the gear or rim P'. In this rim are formed the bearings l and l', in this case four sets, in which are journaled the wiping-rolls N, extending radially inward and having their inner ends reaching to the plug I. These rolls are each composed of an arbor n', on the end of which is the roll proper, which is made of somewhat larger diameter on its inner end than on its outer. The rolls, when in position, are directly over the annular top of the can and extend from the mouth to the edge. Each roll, as here shown, is formed in one piece, and it has two longitudinal slots cut in it at right angles to each other, these slots extending from the end back to the arbor. In these slots are inserted the rubber flanges n in two pieces, each piece having two operating-edges, as shown in Fig. 4. All the parts of the roll are held firmly in place by the single screw n², passing through two opposite segments.

To the fly-frame L is attached one or more ribs or wings L², which fit more or less perfectly the casing R by which the parts are inclosed. This casing R has an opening in one side leading tangentially out from it, and thence communicating with a vertical pipe R', by which the liquid, &c., taken from the top of the can is carried away.

On the arbor n' there is a pinion O (here

shown as a friction roll or pinion) adapted to engage with the friction-gear P' , although it may equally well be an ordinary toothed pinion.

5 Clamped in the upright G there is a horizontal arm b , adjustable longitudinally, and on the end of this arm is the centering-guide F , by which the cans E are centered beneath the wiping-gear. The can rests, when in position, on a base or rest B , which is raised to bring the top of the can in contact with the wiper. When at its lower position, it is flush with the surface of the table. When down, the base B rests on a cross-piece C , through 15 which passes the vertical stem b' , to the upper end of which the base B is secured. A vertically-adjustable stop or collar b^2 is secured to the stem b' by means of a set-screw b^3 . A foot pedal or lever D is provided beneath the table to raise and lower the base B .

The operation of my wiper is as follows: The can being placed on the base B , the treadle D is depressed and the can raised until the stop b^2 strikes against the cross-bar C , when 25 the top of the can will be brought in contact with the rolls N . The two band-pulleys Q and Q' are rotated in opposite directions, and, as a consequence, the friction-gear P' and the fly-frame L move in contrary directions. The 30 gear P' thus turns the pinion O , making the rolls N rotate very rapidly. As a result the liquid or other substance which has collected on the surface of the can will be swept away and forced against the side of the casing, 35 whence it will be taken to the pipe R by the wing L^2 and carried away.

It will be observed that there are two motions, both tending to clean the top of the can, one being the centrifugal motion caused by 40 the rotation of the fly-frame and the other the scouring effect of the revolving wiping-rolls.

It is evident that the flexible ribs of the wiping-rolls may be replaced by flexible pins 45 or other similar devices which will have a scouring effect.

I claim—

1. In a machine for wiping cans, the combination of a rotating fly-frame and rotating 50 wiping-rolls journaled radially thereto, substantially as described.

2. In a machine for wiping cans, the combination of a rotating fly-frame, rotating wiping-rolls journaled radially thereto, and flexi-

ble flanges secured longitudinally to said 55 rolls and adapted to fit the top of said can, substantially as described.

3. In a can-wiping machine, the combination of a rotating fly-frame and rotating wiping-rolls journaled in the outer edge or rim 60 thereof and extending inward over the top of the can, substantially as described.

4. In a can-wiping machine, the combination of a rotating fly-frame, wiping-rolls journaled radially thereto, a pinion secured to 65 each of said rolls, and a tooth-gear for engaging said pinion and rotating the same, substantially as described.

5. In a can-wiping machine, the combination of a vertical shaft, a plug secured to the 70 lower end thereof and adapted to enter the mouth of the can, and a fly-frame rotating about said shaft and having wiping-rolls journaled to it, the inner ends of said rolls extending to or nearly to said plug, substantially 75 as described.

6. In a can-wiping machine, a vertical shaft, a plug or stop secured to the lower end thereof, an inner sleeve fitting said shaft and having at its lower end a gear, an outer sleeve fitting 80 over said inner sleeve and having at its lower end a fly-frame with wiping-rolls journaled thereto, and pinions on said wiping-rolls adapted to engage said gear, substantially as described.

7. In a can-wiping machine, a vertical shaft, a plug or stop at its lower end, an inner sleeve fitting said shaft and having at its lower end a gear, an outer sleeve fitting over 85 said inner sleeve and having at its lower end a fly-frame with wiping-rolls journaled thereto and adapted to engage said gear, and pulleys for said outer and inner sleeves, whereby they are rotated in opposite directions, substantially as described.

8. In a can-wiping machine, a fly-frame, a casing surrounding it and a passage leading tangentially therefrom, and a rib or wing on 90 said fly-frame filling or nearly filling said casing, whereby all liquid is carried to said passage, substantially as described.

In testimony whereof I affix my signature in presence of two witnesses.

PERLEY D. CUMMINGS.
